UNITED STATES PATENT OFFICE.

WILLIAM H. LESH, OF DES MOINES, IOWA.

RAIL JOINT AND CHAIR.

1,075,044.

Specification of Letters Patent.

Patented Oct. 7, 1913.

Application filed November 3, 1911. Serial No. 659,565.

To all whom it may concern:

Be it known that I, WILLIAM H. LESH, a citizen of the United States of America, and resident of Des Moines, Polk county, Iowa, **5** have invented a new and useful Rail Joint and Chair, of which the following is a specification.

The object of this invention is to provide an improved construction for railway rail joints.

A further object of this invention is to provide improved means for supporting abutting end portions of railway rails.

A further object of this invention is to **15** provide improved means for connecting abutting end portions of railway rails so as to permit expansion and contraction of said rails in any direction without damage to the connecting means.

20 My invention consists in the construction, arrangement and combination of elements hereinafter set forth, pointed out in my claims and illustrated by the accompanying drawing, in which—

25 Figure 1 is a plan of portions of abutting railway rails embodying my improvements. Fig. 2 is a side elevation of the same. Fig. 3 is an opposite side elevation of the same. Fig. 4 is a vertical cross-section on the indicated line 4—4 of Fig. 1. Fig. 5 is a side elevation of a shoulder bolt employed in my construction and Fig. 6 is an elevation at right angles to Fig. 5. Figs. **30** 5 and 6 are on a scale enlarged relative to **35** the other views.

In the construction of the device as shown the numerals 10, 11 designate abutting end portions of railway rails. The ball or tread, web and central portion of the base of each **40** rail 10, 11 is cut on an angle of 45 degrees as at 12 and the remaining portion of the base on each side is cut perpendicular to the longitudinal trend of the rail as at 13. The ends of the rails 10, 11 normally are **45** spaced apart as shown to permit of longitudinal expansion under the influence of climatic conditions. A chair 14 supports both end portions 10, 11 and is in turn supported at its ends by end portions of cross-ties 15, 16 of any desired material. The **50** chair 14 is formed with a truss web 17 of any desired shape on its lower face and between the cross-ties 15, 16. It is the function of the truss web 17 to stiffen and strengthen the chair 14 and to prevent

breaking or sagging thereof and sagging of the joint of the rails 10, 11. Angle fish-plates or splice bars 18, 19 are mounted on opposite sides of the rails 10, 11 and overlie the joint thereof. The splice bars 18, 19 **50** are spaced from the webs and base flanges of the rails to permit of expansion and contraction of the rails in any direction under the influence of changes of temperature independent of the splice bars. The splice **55** bars 18, 19 are secured to the rails 10, 11 by means of spaced bolts 20 passing through their vertical flanges and through the webs of the rails and secured by nuts 21 on their threaded end portions. The bolts 20 are **60** formed with shoulders 22 (see Figs. 5 and 6) throughout a considerable portion of their lengths and said shoulders are of elliptical form in cross-section, or are flattened and formed with rounded edges. In **65** one dimension the shoulders 22 are of approximately the same thickness as the body of the bolt as shown in Fig. 6, and in the other transverse dimension said shoulders are considerably thicker than said body. The shoulder of each bolt 20 is received within and fits snugly to an elliptical hole in the upright flange of the splice bar 18 and passes loosely through a slot 23 in the web of the rail 10 or 11. The shoulder 22 **70** projects slightly beyond the farther side of the web of the rail and the body of the bolt 20 is received within and fits snugly to a circular hole in the upright flange of the splice bar 19 and the inner face of said splice **75** bar rests against the end of the shoulder 22 and is held thereby in spaced relations to the web of the rail. Thus when the nut 21 is tightened on the bolt 20 force will be applied to draw the splice bars 18, 19 together **80** so far as permitted by the shoulder 22, but no force will be applied on the web of either rail by the bolt or by either splice bar. The splice bars 18, 19 also are secured to the rails **85** 10, 11 by means of spaced vertical bolts 24 passing through their base flanges and through the base flanges of the rails on each side.

The bolts 24 are similar in construction to the bolts 20 above described and the shoulders thereof are received within and fit snugly to elliptical holes in the chair 14 and pass loosely through longitudinal slots **90** 25 in the base flanges of the rails. The base flanges of the splice bars 18, 19 rest on the **95** 110

ends of the shoulders of the bolts 24, which shoulders project slightly above the upper surfaces of the base flanges of the rails, thus supporting the splice bars in spaced relations to said rails. The body portions of the bolts 24 pass through and are fitted to circular holes in the base flanges of the splice bars 18, 19 and said splice bars are preferably formed with plateaus or bosses 26 surrounding said holes and formed with level upper faces against which the nuts 27 are adapted to be screwed on the bolts. Thus when the nuts 27 are tightened on the bolts 24 force will be applied to draw the base flanges of the splice bars 18, 19 toward the chair 14 so far as permitted by the shoulders of the bolts; but no force will be applied to the base flanges of either rail by the bolt or by said splice bars.

In practical use the trussed chair 14 provides a firm support for the rail joint and prevents sagging thereof under the weight of the rolling stock. The diagonal cutting of the ends of the rails 10, 11 causes them to form conjunctively a continuous tread surface and prevents undue wearing of the ends of the rails. The spacing apart of the ends of the rails and the formation of longitudinal slots in the webs and base flanges thereof to receive loosely the connecting bolts 20, 24 permits of longitudinal expansion and contraction of the rails and the spacing of the splice bars 18, 19 from the webs and base flanges of the rails by the shoulders of the connecting bolts permits said longitudinal expansion and contraction and any lateral and vertical expansion and contraction of the rails that may occur under changes of temperature. This expansion and contraction of the rails in no manner affects the connecting bolts and can not result in shearing off said bolts or loosening the nuts thereof by movement of the rails, as is common in the ordinary construction of rail joints.

I prefer to make the chair 14 with outstanding apertured ears 28, 29 on opposite sides of its respective ends, and to secure said chair to the ties 15, 16 by means of bolts 30, 31 passing through said apertured ears and through the ties. This lends solid-

ity to the joint and prevents creeping of the rails.

I claim as my invention—

1. A rail joint, comprising, in combination, abutting ends of rails, a trussed chair adapted to be supported at its ends and supporting abutting end portions of the rails, angle splice bars on opposite sides of and overlapping the joint between said rails, bolts connecting middle portions of said splice bars through the webs of said rails, said bolts formed with shoulders adapted to hold the splice bars in spaced relations to the rails, said rails formed with longitudinal slots loosely receiving said bolts, and bolts connecting marginal portions of said splice bars to the chair and passing loosely through the base flanges of the rails.

2. A rail joint, comprising, in combination, abutting ends of rails, a suitable support therefor, fish-plates on opposite sides of and overlapping the joint between said rails, and bolts fitting snugly in holes in said fish-plates and passing through longitudinal slots in the webs of the rails, said bolts formed with shoulders adapted to limit movement of said fish-plates toward the webs of the rails, whereby said rails may expand or contract in any direction without damage to said connecting bolts.

3. A rail joint, comprising, in combination, abutting ends of rails, a trussed chair supporting end portions of said rails, angle splice bars mounted on opposite sides of and overlapping the joint between said rails, bolts connecting said splice bars through the webs of the rails, said webs formed with slots adapted loosely to receive said bolts, and bolts connecting said splice bars to said chair through the base flanges of the rails, said base flanges formed with slots loosely receiving said bolts, said splice bars being spaced by said bolts laterally and vertically from said rails.

Signed by me at Des Moines, Iowa, this 22d day of April, 1911.

WILLIAM H. LESH.
